UNITED STATES PATENT OFFICE.

THOMAS D. BRYAN, OF LINDEN, CALIFORNIA.

LOCKING RING FOR SEPARABLE RIMS.

Application filed August 8, 1922. Serial No. 580,461.

To all whom it may concern:

Be it known that I, THOMAS D. BRYAN, a citizen of the United States, and a resident of Linden, county of San Joaquin, and State of California, have invented a new and useful Locking Ring for Separable Rims, of which the following is a specification.

The present invention relates to improvements in separable rims for motor vehicles and its particular object is to provide a locking ring for the rim of the character described. It is proposed to provide a locking ring that can be easily secured in place and easily removed. It is further proposed to use a simple flat ring for this purpose which engages one side of the felloe and extends beyond the same for holding the rim in place. It is further intended to provide means which will firmly lock the ring so as to prevent the same from working loose after it has been secured in place.

The preferred form of my invention is illustrated in the accompanying drawing in which Figure 1 represents a side view of a wheel having my ring attached thereto, Figure 2 an enlarged detail view showing the particular construction of my locking means, Figure 3 a cross-section along line 3—3 of Figure 1, Figure 4 a cross section along line 4—4 of Figure 2 and Figure 5 a section taken along line V—V of Figure 2, showing the locking means both in an operative and in an inoperative position. While I have shown only the preferred form of the invention I wish to have it understood that various changes or modifications may be made within the scope of the claim hereto attached without departing from the spirit of the invention.

The felly band (2) is provided with one radially extending circumferential flange (5) and is permanently secured to the felly in any suitable manner. The tire (4) is held on the band (2) by the separable annular flanges (15) and (18). The flange (15) abuts against the flange (5) and is restrained from lateral movement off the band (2) thereby. The principal feature of the present invention is a means for holding the flange (18) in operative position, which means consists of the locking ring (6). The dimensions of the ring (6) are such that it covers a large portion of the face of the felly (3) and extends beyond its peripheral outer line sufficiently far to contact with the lat-

eral outer face of the flange (18). The felloe is provided with a plurality of transverse bolts (7) terminating at the outside of the felloe in projections (8) rising from the face of the felloe on an incline as shown in Figure (4). These projections are preferably of rectangular cross-sections. The ring (6) is provided with a corresponding number of slots (9) adapted to engage the slanting projections of the felloe. It will be readily seen that in order to secure the ring to the felloe it is necessary to cause the slots to register with their respective projections and to slightly turn the ring to complete the engagement. This turning motion is brought about by means of the cam (11) secured on a pin (12) rotatably supported in the felloe (3). The cam operates in a perforation (13) in the ring and when the pin (12) is turned to the right the cam forces the whole ring to the right whereby the latter due to the engagement of its slots with the slanting projections of the felloe is pressed tightly against the latter. The pin (12) may be actuated by any suitable means, as for instance, by a monkey wrench engaging its squared end (14).

To lock the cam in its final or active position I provide a lock nut (16) which threadedly engages the pin (12) in adjacent relation to the cam (11). This nut is shaped so as to normally not project over the outlines of the cam (11) and therefore does not interfere with the pressing of the ring on the felloe nor with the turning operation. After the ring has assumed its final position the lock nut may be turned a little further than the cam by means of a wrench engaging its flat sides (17) and it will then project beyond the outlines of the cam and engage the marginal portion of the ring defining the recess (13) with a resulting binding action between the nut and the ring which prevents the former from working loose and holds the cam in place.

The operation of my device will be readily understood from the foregoing description. To secure the ring in place it is only necessary to engage the slots (9) with the projections (8) and to then turn the pin (12) by means of a wrench when the cam (11) will force the ring in close contact with the felloe. The operator may then give a slight additional turn to the lock nut (16) which will engage the margin of the ring and bear on

the same so as to lock the whole combination.
I claim:

Locking means for an annular element separably disposed on a felloe, comprising a ring, slanting means associated with the felloe adapted to engage the ring and means for imparting rotary motion to the ring rel-

ative to the felloe, comprising a transverse pin rotatable in the felloe having a cam thereon engaging a slot in the ring and a nut threadedly engaging the pin adapted to bear on the margin defining the slot for holding the cam in its active position.

THOMAS D. BRYAN.
